UNITED STATES PATENT OFFICE.

GEORGE CUGLEY, OF SPRINGFIELD, OHIO, ASSIGNOR TO THE BUCKEYE INCUBATOR COMPANY, OF SPRINGFIELD, OHIO, A CORPORATION OF OHIO.

HEATER.

1,111,137.

Specification of Letters Patent. Patented Sept. 22, 1914.

Application filed July 19, 1913. Serial No. 779,959.

To all whom it may concern:

Be it known that I, GEORGE CUGLEY, a citizen of the United States, residing at Springfield, in the county of Clark and State 5 of Ohio, have invented certain new and useful Improvements in Heaters, of which the following is a specification.

This invention relates to improvements in heaters, especially adapted for incubators.

10 The object of my invention is to provide a heater which will be so constructed as to eliminate all danger from fire.

A more particular object of my invention is to provide a heater in which a 15 permanently fixed support is provided for the lamp and to so arrange the other parts that the lamp may be readily removed and replaced.

20 A further object of the invention is to simplify and make more effective devices of this character.

In the accompanying drawings: Figure 1 is a side elevation of a device embodying my improvements showing the parts in position for use. Fig. 2 is also a side elevation but showing the parts in a position to permit the removal or replacing of the lamp. Fig. 3 is a vertical section of the heater showing the lamp in position therein.

25 Like parts are represented by similar characters of reference in the several views.

In apparatus of this character, one of the forms of heat circulating devices employed consists of a boiler formed with an open 30 central portion, and there is also employed for generating the heat, an oil lamp, the chimney of which extends up through the open central portion of the boiler, in consequence of which it has previously been 35 necessary to support the heating device upon a removable base in order that it may be dropped down sufficiently to permit its flue to clear the parts of the heat circulating device upon being removed or replaced. In 40 order that it may be readily accomplished it has also been common to attach this removable heater support with the main casing of the apparatus in a manner to permit the ready detachment of the parts, such as 45 by spring catches. Such a manner of supporting the heater, however, is dangerous and has been condemned for the reason that the parts are liable to become detached, allowing the heater to fall and thereby causing 50 fire. In order to overcome this ob-

jection I have provided a permanent support for the lamp and devised other means for permitting the removal and replacement of the same.

In the accompanying drawings, 1 represents a main casing of the usual design, having an open side and also provided with ears 2 by which it may be connected with the wall *a* of the incubator or other device with which the heater is used. The heat 60 circulating device, in the present case is a boiler, and its jacket. The boiler is represented by 3 and is of the usual construction in that it has an open central portion and an annular water space to which are 65 connected the usual circulating pipes 3^a. This boiler is removably supported within the boiler jacket 4, which is provided with a series of ribs 5 to provide a space between the jacket and the boiler for the circulation 70 of the heat. The jacket in the present case differs from the style of jackets heretofore employed in that it has a telescoping portion 4^a formed with a central upwardly extending flue 6; the part 4 of the jacket being 75 permanently attached at its upper out-turned end to the upper end of the casing 1 so as to make it immovable or stationary. The two parts of the jacket are arranged 80 to be connected together by a bayonet joint 85 as shown in Figs. 1 and 2; the upper stationary member of the jacket having a laterally projecting pin 7, and the lower movable portion of the jacket having a slot 8 reached by a flaring mouthed opening 9 so 90 that the removable portion may be hooked over the pin in the manner shown in Fig. 2 to hold the removable portion in raised position.

The lower portion of the main casing 1 95 has riveted thereto a bottom portion 10 which has two cross members 11 which form a support for the heating device, in the present case a lamp 12. This lamp 12 is of any suitable form but in the present case is 100 provided with a short chimney 13 over which the flue portion 6 of the boiler jacket is adapted to telescope so as to form a continuation of the chimney and in effect a part thereof.

105 In the operation of the device, when it is desired to remove the lamp the movable portion 4^a of the boiler jacket is raised and suspended on the pin 7 as shown in Fig. 1. This disconnects the lamp chimney and flue 110

- portion 6 and permits the lamp to be removed through the open side of the casing 1. Upon replacing the lamp, the portion 4^a is disconnected from the pin 7 and slid 5 downwardly on the permanent portion 4 until the flue portion 6 telescopes the short chimney 13. This short chimney portion 13 is of sheet metal of gradually decreasing diameter toward the top so that it not only 10 provides a support for the movable portion 4^a of the boiler jacket but also provides a more or less tight joint between its upper end and the flue portion 6 and permits the ready telescoping of the parts.
- 15 By this construction it will be seen that the supports 11 for the lamp are permanent supports in that they are permanently fixed to the main casing 1, thus obviating all danger of the lamp falling out of the device 20 when in use, and at the same time means are provided for permitting the ready removal and replacing of the lamp.

Having thus described my invention, I claim:

- 25 1. In a heating apparatus, a boiler formed with an open center, a boiler jacket, said jacket being formed with a movable portion having a flue extending into the open central portion of said boiler, a heater, a permanent support for said heater, and a flue 30 connected with said heater and communicating with said boiler jacket flue.
2. In a heating apparatus, a boiler having an open central portion, a boiler jacket formed with two telescoping parts, one of 35 which is movable and the other of which is

stationary, a flue carried by the movable portion of said boiler jacket and entering the open central portion of said boiler, a heater, a permanent support for said heater, and a flue connected with said heater and adapted to telescope with said boiler jacket flue.

3. In a heating apparatus, a main casing, a boiler jacket connected with said casing, 45 said boiler jacket having a movable telescopic portion, a boiler formed with an open central portion supported in said jacket, a flue connected with the movable portion of said jacket and arranged in the open central 50 portion of said boiler, a heater, a permanent support at the lower end of the main casing for said heater; and a flue connected with said heater adapted to telescope with the said boiler jacket flue.

4. In a heating apparatus, a main casing, a boiler jacket connected with said casing, said boiler jacket having a movable telescopic portion, a boiler formed with an open central portion supported in said jacket, a 60 heater, a permanent support at the lower end of said main casing for said heater, and a flue connected with the movable portion of said jacket and adapted to communicate with said heater, said flue extending into the 65 open central portion of said boiler.

In testimony whereof, I have hereunto set my hand this 3rd day of July 1913.

Witnesses:

GEORGE CUGLEY.

CHAS. I. WELCH,
ESTHER E. PFEIFER.
